US0D1015995S

(12) **United States Design Patent** (10) **Patent No.:** **US D1,015,995 S**
(45) **Date of Patent:** **** Feb. 27, 2024**

(54) **STORAGE BAG**

(71) Applicant: **Foshan Wanyue Technology Co., Ltd.**,
Guangdong (CN)

(72) Inventor: **Xiaodong Liang**, Guangdong (CN)

(73) Assignee: **Foshan Wanyue Technology Co., Ltd.**,
Guangdong (CN)

(**) Term: **15 Years**

(21) Appl. No.: **29/895,248**

(22) Filed: **Jun. 20, 2023**

(51) LOC (14) Cl. **12-16**

(52) U.S. Cl.

USPC **D12/426**; D3/315

(57) **CLAIM**

The ornamental design for a storage bag, as shown and described.

DESCRIPTION

FIG. 1 is a front, left and top perspective view of a storage bag, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the storage bag that form no part of the claimed design.

1 Claim, 8 Drawing Sheets
